UNITED STATES PATENT OFFICE.

ALBERT E. NEWTON AND ARTHUR C. MERRIMAN, OF LEOMINSTER, MASSACHUSETTS.

DESIGN FOR A BACK COMB.

No. 39,675.

Specification for Design.

Patented Dec. 1, 1908.

Application filed August 18, 1908. Serial No. 449,189. Term of patent 14 years.

To all whom it may concern:

Be it known that we, ALBERT E. NEWTON and ARTHUR C. MERRIMAN, citizens of the United States, residing at Leominster, in the county of Worcester and State of Massachusetts, have invented a new, original, and ornamental Design for Back Combs, of which the following is a specification, reference being had to the accompanying drawings, forming part thereof.

The figure is a perspective view of a comb, showing our new design.

We claim:

The ornamental design for a back comb, as shown.

ALBERT E. NEWTON.
ARTHUR C. MERRIMAN.
